BODY AND CHASSIS UNDERFRAME

Joseph Ledwinka and John W. Kelly, Philadelphia, Pa., assignors to Edward G. Budd Manufacturing Company, Philadelphia, Pa., a corporation of Pennsylvania

Original application April 20, 1936, Serial No. 75,375. Divided and this application April 1, 1939, Serial No. 265,456

3 Claims. (Cl. 296—28)

The invention relates to a vehicle body and particularly to a combined body and chassis construction. More specifically the invention refers to a construction in which the underframe is co-ordinated with the body superstructure to provide box section side sills which may extend from end to end of the combined structure. This application is a division of application Serial No. 75,375, filed April 20, 1936, on which Patent 2,188,267, "Combined body and chassis underframe" was issued on January 23, 1940, to the same applicants.

It is an object of the invention to simplify the construction of such structures and to lighten their weight without materially affecting their strength.

A further object of the invention is to provide a construction which permits the use of light gauge stock and to so arrange the joints entering into the structure as to facilitate their attachment by spot welding.

Other and further objects and advantages and the manner in which they are attained will become apparent from the following detailed description when read in connection with the drawings forming a part hereof.

In the drawings,

Fig. 1 represents in side elevation a sedan type of combined body and chassis structure in accordance with the invention.

Fig. 2 is an enlarged detailed sectional view through the threshold substantially on the line indicated by the line 2—2 of Fig. 1.

Fig. 3 is a detail sectional view on an enlarged scale taken substantially on the line 3—3 of Fig. 1 and looking in the direction of the arrows.

Fig. 4 is a detail sectional view through a cross member taken substantially on the line 4—4 of Fig. 2.

Figs. 5 and 6 are sections corresponding to Figs. 2 and 3 showing a modified form of the invention.

Figs. 7 and 8 are sectional views corresponding to Figs. 2 and 3 showing a further modification of the invention.

In a body according to the invention the sheet metal body floor panel constitutes a main element of the combined underframe structure and may extend from the extreme rear of the combined structure to the extreme front and from side to side of the structure. This floor panel is designated generally by the numeral 29 in Figs. 2, 3 and 4. At the front it may be cut away in the central region to accommodate the motor and at each side of this central opening it may be

suitably reinforced by a marginal reinforce extending around the opening. Alternatively the floor panel may end at the front in the region of the cowl and suitable separate forward extensions for supporting the motor and the front wheel suspension may be provided, such extensions being secured to the reinforced box section side sills of the underframe rearwardly thereof by a telescoping or other suitable joint. The present invention is concerned more particularly with utilization of this floor panel to form box section elements of the combined body and chassis frame, and the sheet metal body side panel indicated generally by the numeral 33 and extending from extreme front to extreme rear of the structure cooperates with the floor panel in forming these box section structures. In this way the combined structure may be built up with the minimum number of parts and the marginal portions of the parts entering into the structure are so shaped as to facilitate their joinder by spot welding.

In the construction shown in Fig. 2, the floor plate designated generally by numeral 29 is formed with a deep vertical web 30 which in turn is formed with a horizontally extending bottom flange 31 terminating in a downwardly extending edge flange 32. The body side panel 33 is joined at the bottom to the flange 32 and at the top the threshold portion 34 terminates in an upwardly extending flange 35 which is joined to the top of the floor plate 29 by a longitudinally extending bridging strip closing the box and designated 36, this bridging strip being formed with an upwardly extending flange 37 overlapping and spot welded to the flange 35 of the outer body panel, its inner margin overlapping the top of the floor plate 29 and being spot welded thereto. In the wheel housing region where the outer panel 33 extends upwardly to form the upper part of the wheel housing, the flange 37 seats in an offset provided in the outer panel and is spot welded thereto in the offset. To space the top and bottom walls of the box in this region the outer panel 33 is offset slightly between the top bridging plate 36 and the bottom outwardly extending flange 31 of the floor plate as clearly appears in Fig. 3.

At suitable points the floor panel which itself forms a cross connection between the side sills is further reinforced by transverse members of channel section, as indicated at 38 and 39 which are preferably formed of upwardly facing channel members secured to the floor panel to form a

strong box section transverse reinforce between the sills.

In the region of the thresholds as shown in Figs. 2 and 4, the upwardly facing channel cross member 38 extending from side sill to side sill is formed at the top with the flanges 20' and 21' laterally extending from its side walls, which flanges are welded to the floor plate 29 to form therewith box section cross members between the sills.

To further strengthen the connection between these cross members and the side sills, the laterally extending flanges 20' and 21' are welded not merely to the single sheet of the floor panel but are extended underneath the inwardly extending double thickness of metal formed by the joinder between the bridging strip 36 and the floor plate 29 and spot welded to this double thickness extension from the inner side of the box section sills. To still further strengthen the joinder between the cross members and the side sills the side walls of the cross member 38 are laterally flanged at their ends as indicated at 22 and 23, see Figs. 2 and 4, and these lateral flanges overlap the vertical web 30 of the floor panel forming the inner wall of the box section and are secured thereto by spot welding. Similarly, an extension of the bottom wall of the channel 38 is extended and spot welded to the lower wall 31 of this box section side sill.

In the region of the wheel housing the cross member 39 forms in similar manner a box section cross member with the floor plate 29 and is secured to the box section side sill extending through this region in substantially the same manner as in the form shown in Figs. 2 and 4.

In the modification shown in Figs. 5 and 6, the floor plate 40 is extended straight out to the body side panel 42 except for a slight upward offset in the region of the side sills and is flanged upwardly at its margin at 41 and secured to the body side panel indicated in these figures by numeral 42 in identically the manner in which the bridging strip 36 is secured to the side panel, in the modification of Figs. 2 and 3. The outer panel 42 in this case forms the outer wall of the box section sill in the same manner as in the form shown in Figs. 2 and 3, but the inner wall of the box section and at least part of the bottom wall of the box section are in this case formed by a separate sill element 45 of outwardly facing channel section, the top wall of the channel overlapping the floor plate 40 in the offset and being secured thereto by spot welding while the bottom wall of the channel is flanged downwardly at 46 and secured through this flange to the lower margin of the body side panel 42 in the same manner as that indicated in Figs. 2 and 3. The cross members 47 and 48 are again secured to the floor plate and to the box section side sills in substantially the same manner as that shown in the earlier figures.

In the modification shown in Figs. 7 and 8 the construction is very similar to that shown in Figs. 5 and 6 except that a Z member 49 has been substituted for the channel member 45 and the outer margin of the floor plate 50 is offset downwardly to form a shoulder against which the top of the Z member may seat, the top arm 51 of the Z member being secured to the floor plate as shown and the bottom arm 52 being flanged in its margin at 53 and secured to the outer panel designated 54 in identical the manner shown in Figs. 5 and 6.

The cross members 55 and 56 shown respec-

tively in Figs. 7 and 8 are secured to the side sills again in substantially the manner shown in Figs. 2 to 6. However, where the lateral flanges from the side walls as 57 overlap the double thickness of the metal of the flange 51 and the floor plate 50, they are downwardly offset as at 58.

In both these latter forms shown in Figs. 5, 6, 7 and 8 the floor plate combines with the outer side wall panel just as it does in the form shown in Figs. 2 and 3 to form elements of the box section underframe structure. It will be noted that in all embodiments a third member cooperates with the floor plate and the side panel to form the complete box section framework.

All of the modifications described lend themselves very readily to manufacture out of light gauge metal, although in some cases the separate side sill elements 45 and 49 may be made of heavier gauge than the floor plating and the side paneling if desired for greater strength, and in all of these constructions use is made of both the side paneling and the floor plating to form elements of the box section side sill and cross member structures respectively, and the parts are so formed as to facilitate their joinder by simple spot welding operations. Other modifications of the invention may occur to those skilled in the art, and it is desired in the following claims to include such modifications within the purview thereof.

The specific construction of the side sills illustrated in Figures 2 and 3 forms the subject matter of applicants' application Serial No. 519,422, Combined body and chassis structure, filed January 24, 1944, as a division of the present application.

What we claim is:

1. In a vehicle body, an upstanding side wall member, a floor panel, a longitudinal side sill member, a transverse sill member having one of its ends rigidly fastened to said side sill member, said side sill member being of hollow section form and having an open side facing outwardly in a direction away from the longitudinal center line of the body, said transverse sill member being likewise of hollow section form having an open side facing upwardly, said open sides of said sill members being closed respectively by a lower marginal portion of said side wall member and said floor panel, the latter having its longitudinal side margin additionally fastened to said side sill member.

2. In a vehicle body, an underframe unit comprising longitudinal side sill members interconnected by transverse sill members, said side sill members being of outwardly facing channel form and at least one transverse sill member being of upwardly facing channel form, body sidewall structures having their lower marginal portions fastened to the upper and lower margins of said side sill members as to form closed box sectional side sills, a body floor panel structure having its margins fastened to said side sill structures and being furthermore fastened along transverse lines to the upstanding walls of said channel formed transverse sill member as to form a closed box sectional cross brace therewith.

3. In a combined chassis and body structure substantially entirely of sheet metal; a pair of transversely spaced longitudinal sheet metal side sill members extending over substantially the entire length of the structure including a threshold and a wheel housing region; each of said sill members having an upstanding arm, a horizontal

arm along the upper margin and a horizontally outwardly directed arm along the lower margin of said upstanding arm, and a downwardly directed flange along the outer edge of said outwardly directed arm; a pair of body sheet metal side wall panels provided with threshold and wheel housing portions the lower margins of which overlap and are connected throughout their lengths to said flanges; a sheet metal floor panel extending longitudinally at least through the threshold and wheel housing regions and transversely from side wall panel to side wall panel; an upwardly directed flange along each longitudinal margin of said floor panel; said floor panel resting on and being secured to said

horizontal arms along the upper margins of said sill members and overlapping and being secured to the interior of said side wall panels by means of its marginal flanges; said sill members, said side wall panels and said floor panel constituting together a combined body and a chassis frame structure having closed box sectional side sills extending over the entire length of the body and their assembly being facilitated by the fact that said flanges connecting the sill members and the floor panel to the side wall panels extend outwardly from the box sections.
